J. W. KUMMER.
COMBINATION RAIL SEAT, TIE PLATE, AND RAIL TIE CLAMP.
APPLICATION FILED DEC. 7, 1920.

Patented June 7, 1921.
2 SHEETS—SHEET 2.

UNITED STATES PATENT OFFICE.

JOHN WILLIAM KUMMER, OF SEATTLE, WASHINGTON.

COMBINATION RAIL-SEAT, TIE-PLATE, AND RAIL-TIE CLAMP.

1,380,979.

Specification of Letters Patent.

Patented June 7, 1921.

Application filed December 7, 1920. Serial No. 428,933.

To all whom it may concern:

Be it known that I, JOHN W. KUMMER, a citizen of the United States, residing at Seattle, in the county of King and State of Washington, have invented certain new and useful Improvements in Combination Rail-Seat, Tie - Plate, and Rail - Tie Clamps, of which the following is a specification, reference being had therein to the accompanying drawings.

This invention relates to a combination rail seat, tie plate, and rail tie clamp, and has for its object the provision of simple and efficient means for retaining a railroad rail upon a tie.

With this and other objects in view, my invention comprises certain novel combinations, constructions and arrangements of parts as will be hereinafter described, illustrated in the accompanying drawings, and more particularly pointed out in the appended claims.

In the drawings:

Figure 1 is a fragmentary perspective view of a railroad rail and a tie, showing my improved apparatus assembled therewith, for securing the rail on the tie.

Fig. 2 is a sectional view taken on line 2—2, Fig. 1, and looking in the direction of the arrows.

Fig 3 is a top plan view of the base plate, while

Fig. 4 is a bottom plan view of the same.

Fig. 5 is a perspective view of another embodiment of my U-shaped anchor member.

Referring to the drawings by numerals, 1 designates the tie, and 2 the rail. The base plate 3 rests upon the tie 1, and on the bottom of the base plate are arranged a series 40 of elongated spurs 4; each spur 4 is sharpened (Fig. 2) for facilitating the spur penetrating or sinking into the tie 1, when the rail 2 is placed upon the plate 3. The plate 3 is provided with lateral extensions 5, these 45 extensions being arranged at diagonally opposite corners and at opposite side-edges of the base plate 3. In each lateral extension 5 is an elongated aperture 6. At the side edges of the base plate 3, and integral with the upper portion or face are flange lugs 7 that overhang and rest snug upon the upper 50 face of the base of the rail 2 (Figs. 1 and 2).

To anchor or positively fasten the base plate 3 to the tie 1, I employ a substantially 55 U-shaped anchor member 8, the upper ends 9 of which extend through the elongated

apertures 6 of the lateral or outwardly-extending extensions 5. In the ends 9, of the U-shaped member 8, are formed elongated apertures 10, in which apertures are inserted the wedge keys 11, which keys are split or bifurcated upon their inner ends, so that the bifurcated portions can be spread apart, as shown in Fig. 1, after the keys have been inserted in the apertures 10, thereby holding the U-shaped member 8 upon the tie 1 and plate 3, securing, anchoring, or locking the plate upon the tie and, consequently, holding the rail 2 against displacement off the tie 1.

The base plate 3 is provided with an elongated rail-engaging shoulder 12, which has its inner face formed in the same plane as the inner portion of the flange lug 7 against which it is formed (Figs. 2 and 3); the rail 2 rests snugly under the flange lugs 7 and has one of its edges bearing against the shoulder 12, Fig. 2; this shoulder 12 acts as a guide to direct the rail quickly and easily under the lugs 7 when the end of the rail is being shoved upon the plate 3 for placing the rail in position upon the plate; further, the shoulder acts as an additional brace upon the plate against which some of the strain can be borne if the rail has a tendency to move laterally or sidewise upon the plate 3, against the shoulder 12 and the lug 7 contiguous thereto.

In the embodiment shown in Fig. 5, the upper ends 9a of the U-shaped anchor member 8a are threaded, and these ends are adapted to extend through apertures in extensions 5, as shown in dotted lines (9a) in Fig. 4. Nuts of any ordinary type can be threaded upon threaded ends 9a for positively fastening the U-shaped member 8a upon the tie 1 and plate 3.

In assembling the apparatus, the U-shaped member is first placed under the tie 1, then the plate 3 is placed upon the tie with the ends of the U-shaped member extending through the apertures 6, then the rail is run under the flange lugs 7, being guided in this placement by the strengthening and guiding shoulder 12, and then the wedge keys 11 are placed in the apertures 10 of the U-shaped anchor member 8, whereupon, the keys are driven in tight, which has a tendency to cause the spurs 4 to bite or sink into the tie 1 should these spurs not be in sufficiently far to cause the same to grip the tie by reason of the weight of the rail 2; upon

the keys 11 being tightly driven into the apertures 10, the inner split or bifurcated ends can be spread apart and the entire device will then be fastened securely upon 5 the tie.

While I have described the preferred embodiment of my invention, and have illustrated the same in the accompanying drawings, certain minor changes or alterations 10 may appear to one skilled in the art to which this invention relates, during the extensive manufacture of the same, and, I, therefore, reserve the right to make such alterations or changes as shall fairly fall 15 within the spirit and scope of the appended claims.

What I claim is:

1. In an apparatus of the class described, the combination of a base plate provided at 20 opposite sides and at opposite corners with lateral extensions, said lateral extensions provided with apertures, said base plate provided with rail-engaging means, an anchor member extending at its ends through the apertures of the lateral extensions, and locking means on the extended ends of said anchor member.

2. In an apparatus of the class described, the combination of a base plate provided at 30 opposite sides with lateral extensions, said extensions provided with apertures, said base plate provided with a penetrating spur on its under face, said base plate pro-

vided with flange lugs upon its upper face, said base plate provided contiguous to one 35 of said lugs with an elongated shoulder, and anchoring means in said apertures of the extensions.

3. In an apparatus of the class described, the combination of a base plate provided 40 with lateral extensions upon opposite sides and at opposite corners, said extensions provided with elongated apertures, said base plate provided on its under face with a series of elongated sharpened spurs the 45 spurs being parallel and extending diagonally across the base plate, said base plate provided on its upper face with flange lugs arranged contiguous to opposite side-edges and contiguous to opposite corners, said 50 base plate provided at one of these flange lugs with an elongated shoulder adapted to be engaged by an edge of a rail, a U-shaped anchor member having elongated ends extending through the elongated apertures of 55 the extensions of the base plate, said elongated ends of the anchor member provided with elongated apertures, and split wedge keys in the elongated apertures at the ends of the anchor member and bearing against 60 the upper face of the base plate for causing the base plate and anchor member to be tightly held together.

In testimony whereof I hereunto affix my signature.

JOHN WILLIAM KUMMER.
